(57) CLAIM

The ornamental design for footbed, as shown and described.

DESCRIPTION

FIG. 1 is a front perspective view of footbed;

FIG. 2 is a front view of footbed;

FIG. 3 is a back view of footbed;

FIG. 4 is an inner side view of footbed;

FIG. 5 is an outer side view of footbed;

FIG. 6 is a top view of footbed; and,

FIG. 7 is a bottom view of footbed.

The features shown as dashed lines form no part of the claimed design, and the surfaces enclosed by the dashed lines in FIG. 7 form no part of the claimed design.

1 Claim, 7 Drawing Sheets(56)
